(57) **CLAIM**

The ornamental design for a crosshead pediment, as shown and described.

DESCRIPTION

FIG. 1 is a rear perspective view of my crosshead pediment; FIG. 2 is a left side view thereof, the right side view being a mirror image thereof;

FIG. 3 is a front view thereof;

FIG. 4 is a rear view thereof;

FIG. 5 is a top view thereof; and,

FIG. 6 is a bottom view thereof.

The crosshead pediment is shown broken away in FIGS. 1 and 3-6 to indicate indeterminate length.
